United States Patent Office

Des. 192,853
Patented May 22, 1962

192,853

FOOT PEDAL

Oran C. Wilson, Norwalk, and Richard L. Motter, Milan,
Ohio, assignors to Wilson Plastics, Inc., Sandusky,
Ohio, a corporation of Ohio

Filed Dec. 6, 1961, Ser. No. 67,820

Term of patent 14 years

(Cl. D14—6)

FIG. 1

FIG. 2

FIG. 3

FIG. 4

FIG. 1 is a side elevational view of a foot pedal embodying our new design;

FIG. 2 is a top plan view of the foot pedal of FIG. 1;

FIG. 3 is a bottom plan view of the foot pedal of FIGS. 1 and 2;

FIG. 4 is an end elevational view of the foot pedal as seen from the left of FIG. 1.

We claim:

The ornamental design for a foot pedal, substantially as shown.
